UNITED STATES PATENT OFFICE.

WILLIAM HARPER, JR., OF NEW YORK, N. Y., ASSIGNOR, BY MESNE ASSIGNMENTS,
TO GAS TURBINE CORPORATION, OF NEW YORK, N. Y., A CORPORATION OF DELA-
WARE.

COMBUSTION-ENGINE-VALVE MECHANISM.

Application filed March 7, 1918, Serial No. 220,949. Renewed February 17, 1922. Serial No. 537,360.

To all whom it may concern:

Be it known that I, WILLIAM HARPER, Jr., a citizen of the United States, and a resident of New York city, in the county of New York and State of New York, have invented certain new and useful Improvements in Combustion-Engine-Valve Mechanism, of which the following is a specification.

This invention relates to combustion engines, and has especial reference to aviation engines of the rotary cylinder type.

The objects of the invention are to provide mechanical actuating means for all of the valves, whereby it is possible to increase both the speed and efficiency of this type of engine. Heretofore, difficulty has been encountered in operating these engines at high speeds owing to the inlet valve through the piston not being mechanically actuated, which had the result in practice of being liable to stick and also varying in time of opening. At high speed, the unreliability of such a valve increases, owing to its inertia, with the result that the volumetric efficiency of the engine rapidly decreases, because sufficient charge is not admitted nor are the exhaust gases completely discharged.

By this invention, the inlet valve is mechanically actuated by a cam which is itself moved by the connecting rod, through resilient connections such that the valve is held seated by the cylinder pressure during the working and compression strokes, but is positively and widely opened at the same point of travel in every cylinder for the admission of charge.

The exhaust valve mechanism is operated by external means including a compound leverage such that a relatively large force is applied to initially open the valve against the cylinder pressure with increased leverage for further movement of the valve so as to secure quick and wide opening. The closing movement of the valve is at first rapid and then slow so that it seats easily.

In the accompanying drawings,

Figure 1 is a section showing parts of three cylinders of a nine cylinder rotary motor,

Figure 2 is an end elevation,

Figure 3 is a detail of the inlet valve, on an enlarged scale, and

Figure 4 is a detail of the exhaust valve, on an enlarged scale.

Referring to Figures 1 and 2, 1 repre-

sents the rotary casing carrying air cooled cylinders 2 and rotating around the fixed shaft 3 having a crank pin 4. Rotating on the crank pin 4 is a master ring 5 carrying a rigid connecting rod 6 connected to the piston 7 in one of the cylinders. The other pistons 7 are connected to the master ring 5 by pivoted connecting rods 8 in the usual manner. Each piston has the usual notch 9 in one side to prevent interference between adjoining pistons when at innermost position. The trunk portion of the piston is reenforced by a casting 10 which forms the head 11 and carries the wrist pin. The casting 10 is provided with slots 13 through 19 which the charge passes to inlet valve 12 from the carburetor connected to the casting 1.

The inlet valve 12 has a separable seat 14 and a hollow stem 15 which carries a collar 16. Between the collar 16 and the head 11 is placed a seating spring 17 which normally holds the valve 12 seated. Within the valve stem 15 is telescoping push rod 18 having a limiting shoulder 19 which engages the collar 16, and between the hollow rod 18 and the valve head is interposed another spring 20.

Pivoted at 21 on one of the webs of the piston is a rocker 22 which engages the push rod 18, and is itself operated by an oscillating cam 23 carried on the end of the connecting rods 6, 8. At the extreme ends of the piston stroke, the cam will be in such position that the valve 12 will be seated by the spring 17.

Assuming the piston at its outer position ready to commence the suction stroke, the cam 23 will be under the rocker 22 and about to commence lifting the rocker as the piston moves in. The cam 23 acts on the rocker between the pivot 21 and the end of push rod 18, and consequently the actuating end of the rocker has a multiplied movement on the push rod. This multiplied movement 100 while the piston is going inward towards the center quickly compresses the relatively stiff spring 20 to such extent that it overcomes spring 17 and opens the valve quickly. The valve stays open until the cam moves 105 away from the rocker to such extent that the spring 17 can close the valve, which will be at the inner end of the stroke. The compression now takes place during the outer movement of the piston, during the time 110

when the cam 23 is out of contact with the rocker, thus bringing the piston back to its outer position with the charge compressed ready for firing. During the explosion 5 stroke the pressure in the cylinder prevents the valve from opening even though the cam 23 is compressing spring 20. The exhaust occurs during the succeeding outward stroke of the piston while the cam is below the 10 rocker, thus completing the cycle. Engines of this type are ordinarily lubricated by a spray within the cylinders, which will necessarily reach all the moving parts within the cylinders including the rocker, valve stem, 15 etc. Also, the mechanism is such that the valve is seated gently although operating at very high speed. The valve seat 14 is threaded into the piston head 11 and is so arranged that the valve can be removed as a 20 unit through the cylinder head.

This mechanism will positively and quickly actuate the inlet valve at the same point in the stroke of each cylinder, and the valve can be of sufficient area to enable the full 25 volumetric efficiency of the engine to be obtained at high speeds.

The head exhaust valve mechanism shown in Figures 3 and 4 provides quick opening and easy seating of the valve, with ample 30 area, and enables the full advantages of the inlet mechanism to be realized. 25 is the exhaust valve cooperating with a removable seat 26 of larger diameter than the inlet valve mechanism, before described, so as to 35 permit removal of both valves as units through the cylinder head. 27 is a push rod operated by a cam within the casing and connected to a link 28 which is connected to a lever 29 pivoted at 30 on an arm 40 31 carried by a casting 32 seating on valve seat 26 and having slots for passage of the gases. The valve stem 33 carries a collar 34 to hold the seating spring 35. Pivoted on an arm 36 is a rocker lever 37 having a 45 circularly milled slot 38 in which is seated a block 39 having its shank 40 slidably engaging lever 29, as through pins 41. The lower surface of the block 39 is flat and rests on the rounded end of valve stem 33. Beyond 50 the slot 38, the lever 37 extends to an actuating end 42 which is engaged by lever 29 to initially open the exhaust valve against the cylinder pressure, at which time the lever 29 is relatively short and acts on lever 55 37 with greater force. After the valve has opened and the pressure has been relieved, the extreme end 44 of lever 29 engages with the intermediate portion of lever 37 thereby increasing the throw of lever 37 so as to 60 give a wide opening of the valve. By providing the movable block 39 between the

valve stem and the lever 37, lateral pressure on the valve stem guide 45 is avoided, because the tendency of lever 29 rocking on center 30 to produce lateral pressure on one 65 side is neutralized through the block by the lever 37 rocking on its center on the opposite side, so that the resultant force on valve stem 33 is always in an axial direction. This exhaust valve mechanism does not objectionably increase the total diameter of the engine, and it applies a powerful force to initially open the valve against the cylinder pressure and then a less force through a greater distance to secure wide and quick 75 valve opening. At the same time, this system of compound leverage operates in the reverse direction to gently seat the valve.

The invention is applicable to various purposes and other types of engines than that herein illustrated, but is of particular advantage in the rotary cylinder type of engine by reason of permitting ample valve areas at high speeds, with positive actuation, and also insuring easy seating of the valves. 85 The gases also have practically a straight path through the cylinder, which is essential in high speed engines. By this invention the speed, power and flexibility of a given size of engine will be largely increased, which is of extreme importance in aviation.

What is claimed, is:

1. A combustion engine having a cylinder, crank shaft and connecting rod, a valve in the piston, valve actuating means operated by the connecting rod, and means for multiplying the movement between the actuating means and the valve.
2. A combustion engine having a cylinder, 100 crank shaft and connecting rod, a valve in the piston, valve actuating means carried by the connecting rod, a resilient actuating connection between the valve and the actuating means, and means for multiplying 105 the movement between the actuating means and the valve.
3. A four cycle rotary cylinder combustion engine having a mechanically actuated valve in the piston head held seated against 110 its actuated means by cylinder pressure during alternate like strokes, actuating means including a cam operated by the connecting rod, an opening spring, and a rocker engaged by the cam, a valve in the cylinder 115 head, and external valve actuating means moving the valve at a varying rate during each movement.

Signed at New York city, in the county of New York, and State of New York, this 120 5th day of March A. D. 1918.

WILLIAM HARPER, JR.
